(57) **CLAIM**

The ornamental design for a follower as shown and described.

DESCRIPTION

FIG. 1 is a perspective view of a follower showing the new design from the top, front, and right side;

FIG. 2 is another perspective view thereof, shown from the top, rear, and right side;

FIG. 3 is yet another perspective view thereof, shown from the bottom, rear, and right side;

FIG. 4 is a right side elevation view thereof.

FIG. 5 is a left side elevation view thereof;

FIG. 6 is a front elevation view thereof;

FIG. 7 is a rear elevation view thereof;

FIG. 8 is a top plan view thereof; and,

FIG. 9 is a bottom plan view thereof.

FIG. 10 is a perspective view of another embodiment of a follower showing the new design from the top, front, and right side;

FIG. 11 is another perspective view thereof, shown from the top, rear, and right side;

FIG. 12 is yet another perspective view thereof, shown from the bottom, rear, and right side;

FIG. 13 is a right side elevation view thereof.

FIG. 14 is a left side elevation view thereof;

FIG. 15 is a front elevation view thereof;

FIG. 16 is a rear elevation view thereof;

FIG. 17 is a top plan view thereof; and,

FIG. 18 is a bottom plan view thereof.

The broken lines illustrate features of the follower that form no part of the claimed design.

1 Claim, 16 Drawing Sheets
